UNITED STATES PATENT OFFICE.

HIRAM C. J. DEEKS, OF SEA CLIFF, NEW YORK, ASSIGNOR TO AMERICAN RAYLO CORPORATION, OF NEW YORK, N. Y., A CORPORATION OF DELAWARE.

COLOR PHOTOGRAPHY.

Application filed June 25, 1914, Serial No. 847,298. Renewed November 9, 1920. Serial No. 422,969.

To all whom it may concern:

Be it known that I, HIRAM C. J. DEEKS, a citizen of the United States, residing at Sea Cliff, in the county of Nassau and State of New York, have made a certain new and useful Invention in Color Photography, of which the following is a specification.

This invention relates to the method of color-photography in which the photographic record of the object is divided up into two, three or more parts with the aid of suitable color screens and color sensitive plates, and in which color elements or prints are made from the records thus obtained and are superimposed or blended together on white paper or other suitable base, to form a composite picture portraying the original object in its true natural colors.

The object of my invention is to produce the several colored elements of which a colored photographic print is composed, in purer and more correct hues, and to superimpose and blend them, in a manner simpler, more direct, more accurate and much quicker than has heretofore been possible, into a picture possessing the brilliant and beautiful colors seen in nature to a greater extent than heretofore.

In the accompanying drawings, which disclose apparatus used merely for purposes of illustration—Fig. 1 represents a film stretched tightly upon a metal frame and having thereon three photographic elements containing coloring matter corresponding to the three primary colors; Fig. 2 is a sectional view thereof showing the surface in exaggerated relief; Fig. 3 is a view showing an apparatus for carrying out my invention and Fig. 4 is a sectional view, on a larger scale, of part of this apparatus.

The preferred application of my invention will be more clearly understood from the following brief outline:

I first produce, upon celluloid or other suitable and suitably mounted film, photographic reproductions of the record negatives, by any of the well known bichromate processes, in which the image is composed of coloring matter held in varying amounts by the gelatine, glue or other organic substance employed, proportionately according to the degree in which the said organic substance, having been previously sensitized as with bichromate, has been altered by light. The coloring matter which I use in the present

instance has the property of imparting its color to a recording or permanent film, conveniently a collodion film in an undried state, when brought into contact with the latter. Each of the reproductions respectively is made with a coloring matter which is complementary to the color screen used with the record negative from which the reproduction is made. I then transfer the reproductions thus produced; in the present instance by superimposing them in quick succession, with means for suitable pressure and accurate register, upon and into contact with a recording film, preferably a collodion film; the transfer is made after it has become set and before it is dry, and while spread upon white paper or other suitable support, thereby obtaining a picture in which the colors are represented by dyed collodion.

A detailed description of a selected illustrative application of my invention follows and applies to a three color photograph, but it will be understood that my invention is applicable to a different multiple of colors, and is otherwise not restricted to the disclosed application or embodiment thereof.

In carrying out the illustrative form of my invention a desired coloring matter is first prepared in a very fine state of division and which is insoluble in water or other developer but is soluble in alcohol, ether or other similar solvent. This may be accomplished by dissolving a dyestuff together with a resinous substance, such as gum sandarac, in alcohol. The solution is then sprayed by means of compressed air and a very small orifice in any well known or suitable manner, into a closed chamber whereby the solvent is evaporated and the dyed residue falls to the floor of the chamber in the form of a finely divided colored powder and is readily collected. This coloring matter is preferably prepared in different colors corresponding to the desired number of colors for example the three primary colors which the negatives record, by using different dyestuffs in the solution. For the magenta I use preferably rhodamine, for the blue a mixture of methylene blue and brilliant green and for the yellow auramine.

The several coloring matters are next incorporated with a solution of gelatine in warm water to which has been added a small quantity of suitable matter such as

sugar or corn syrup to prevent cracking of the film when dry. Separate solutions are made of each of the colors.

A sheet of film, such as transparent celluloid, having been previously stretched tightly and fastened in a metal frame of suitable dimensions, or otherwise suitably held, is placed upon a levelling stand and the surface is divided laterally into the required number of, herein three equal portions and temporarily marked by any suitable means. The warm solution of gelatine containing the several coloring matters are then flowed over corresponding portions of the celluloid sheet by pouring thereon the required quantities and spreading evenly with a glass rod. The magenta is spread over one portion, the blue over another and the yellow over the third. The composite film thus produced, after having become set and dried, may be kept for a considerable length of time without deterioration and when required for use may be sensitized as by immersion in a solution of potassium bichromate and dried in the dark, when it is ready for exposure under the negative or negatives.

The three negatives for recording the primary colors of the objects are made with selective color screens in any well known or suitable manner and are preferably made upon a single plate and arranged in lateral juxtaposition so that when the plate is placed in contact with the celluloid sheet having thereon the gelatine film containing the coloring matter, the negative which has been made with the green screen will be in position to print the gelatine containing magenta coloring matter, the negative made with the red screen will be in position to print the gelatine containing blue coloring matter and the negative made with the violet screen will be in position to print the gelatine containing yellow coloring matter.

The sensitized composite gelatine film is then printed in the usual manner by placing it behind the negative in a printing frame and exposing it to light with the plain side of the celluloid against the negative, so that the light, coming through the negative, will pass next through the film and will act first upon the gelatine laying next to the film. After sufficient exposure to light the composite print may be directly developed by immersion in warm water in the usual manner, when the unaltered gelatine will be washed away leaving upon the film three positive images consisting of insoluble colored gelatine in varying amounts corresponding to the action of the light passed by the negative.

The images produced upon the celluloid as above described are illustrated in Fig. 1. 1 represents the metal frame, 2 is the celluloid sheet and 3, 4 and 5 are the gelatine images containing respectively yellow, blue

and magenta colouring matter. Fig. 2 is a sectional view taken upon the plane of the line A B of Fig. 1, 1 represents the metal frame, 2 is the celluloid sheet and 3, 4 and 5 indicate the insoluble gelatine containing the colouring matter.

To transfer the colors of the three photographic elements thus obtained, upon a final support, I may use an apparatus illustrated in Figs. 3 and 4, in which 6 represents a heavy roller designed to furnish sufficient pressure by means of its weight, riding upon rails 7^a and 7^b secured to a baseboard 8. The bar 9 is arranged to slide lengthwise between bearings 10^a and 10^b secured to the baseboard and carries a frame 11 hinged at 12^a and 12^b, adapted to hold, by blocks 13^a, 13^b, 13^c and thumbscrews 14^a and 14^b, the frame 1 holding the celluloid sheet having thereon the photographic elements. In the bearing 10^b is a movable pin 15 arranged to fit into the holes 16^a, 16^b and 16^c of the sliding bar 9 and lock the latter firmly in place during the operation of transferring. The holes 16^a, 16^b and 16^c are made in the bar 9 at a distance apart to correspond with the distance apart of the photographic elements 3, 4 and 5 on the celluloid sheet.

As shown more clearly in Fig. 4, 17 is a removable block having holes 18^a and 18^b adapted to fit the pins 19^a and 19^b fastened in the baseboard 8 and the shape and size of its upper surface corresponds to the shape and size of one of the prints 3, 4 and 5. Block 17 serves to hold temporarily the final support of the picture, which final support may be, for instance, the sheet of white paper which is indicated at 20, having spread upon its upper surface a film of collodion 21. Block 17 also serves as a bed to resist the pressure of the roller 6. The position of the block 17 upon the baseboard 8 is so arranged that when the movable pin 15 held by the bearing 10^b is inserted in the left hand end hole 16^a of the sliding bar 9 it will fit exactly under the left hand end print 3.

It will be understood that when the slide 9 is moved along and the pin 15 is inserted in the holes 16^b or 16^c, the prints 4 or 5 will come into the correct position opposite the block 17.

The first step in the operation of this apparatus is to secure the slide 9 in one position by inserting the pin 15 in one of the holes, say 16^c. The frame 1 holding the celluloid sheet 2 is then placed on the frame 11 with the side having the gelatine prints face downward and is secured thereto against the blocks 13^a, 13^b and 13^c by the thumbscrews 14^a and 14^b. The frame 11 is next raised to an upright position from its hinges 12^a and 12^b to allow of access to the block 17. A sheet of white paper cut to the size of the block 17 is secured temporarily thereto by any suitable means (not shown)

such as, for instance, a small quantity of sticky glue placed at the corners. The block 17 may then be removed from the baseboard and held in one hand while the paper thereon is coated with collodion by pouring on a small quantity and tilting the block to spread and run off the surplus, in the ordinary manner. After a few seconds the collodion will have become set and the block is 10 placed in its position on the baseboard. The frame 11 is then lowered so that the colouring matter held by the photographic image will be brought into contact with the collodion film. A pad 22 composed preferably 15 of resilient material such as, for instance, rubber and of approximately the same size as the paper, is next placed upon the celluloid sheet opposite the block 17. The roller 6 is then made to run slowly along the rails 20 7^a and 7^b over the pad 22 and back again to its original position. The pad 22 should be of sufficient thickness so that the roller, in passing over it, will exert an even pressure upon, and force into close contact, the photographic print with the collodion film. 25

The pad 22 is then removed and the frame 11 is raised to an upright position, when it may be seen that the collodion film has become dyed in exact proportion to the amount 30 of colouring matter, in this case yellow, which was held by the photographic print.

The pin 15 is next removed allowing the slide 9 to be moved along until the hole 16^b is opposite the hole in bearing 10^b, and the 35 pin may be inserted therein. The frame 11 is again lowered, the pad placed on the celluloid opposite block 17 and the operation of rolling repeated. Upon raising the frame it may be seen that the collodion has become 40 dyed blue corresponding to the amount of colouring matter from the photographic print 4. The blue has, however, become blended with the yellow of the first transfer and the picture appears therefore at this 45 stage a mixture of yellow and blue. The slide is next moved to its final position and locked there by inserting pin 15 in the bearing 10^b through the hole 16^a. The operation with pad and roller is repeated and the 50 frame 11 is raised. This last operation has dyed the picture magenta corresponding to the amount of colouring matter which was held by the photographic print 5.

The picture will now appear complete, 55 having become dyed the three primary colors. The paper forming the support of the picture may be removed from block 17 by inserting a knife between it and the block and prying it from the glue which temporarily held it.

A point of real value in this invention is the fact that the action of the solvent of the collodion upon the colouring matter held by the gelatine, when brought into contact 60 with the latter, is to instantly release the

color from the gelatine and transfer it to, and dye therewith, the collodion. It will be understood that the gelatine, in the embodiment of the invention herein used for illustration, acts only as a temporary carrier of 70 the colouring matter and does not form a part of the final picture.

The operation of making the three transfers as above described, can readily be performed within a short space of time, say 75 one minute or less, so that the collodion may be retained in an undried state until the final transfer has been effected.

It will be clearly understood from the above description that the film of collodion 80 upon the paper support has been dyed as many times as there are colors used, herein three times, first in yellow, forming an exact positive corresponding to the violet record negative, second in blue corresponding to 85 the red record negative and third in magenta corresponding to the green record negative, thus forming a complete heliochrome.

Accurate automatic register of the three 90 colors is assured since the spacing of the three holes in the slide may be made to correspond exactly with the distance apart of the three negatives and consequently of the 95 three prints made therefrom upon the celluloid sheet and carried by the slide.

The correctness of hue of the three colors required may be readily obtained because the admixture of dyestuffs in the sandarac-alcohol solution used for making the colouring matter, may be regulated as desired and any basic dyestuff may be used. 100

The brilliance of the colors is assured because the range of basic dyestuffs is very 105 large and includes many very bright colors and also because of the transparent nature of the collodion film and its brilliancy of color when dyed with this class of dye-stuff.

The celluloid sheet held by the metal 110 frame may be cleansed of the photographic print after the color has been transferred therefrom and may be recoated with gelatine and colouring matter and thus used repeatedly. 115

One advantage of my method of producing colored photographic prints is that although it involves the use of soluble color it renders unnecessary the use of dye baths which heretofore were generally required to tint the positive images; among other advantages of the present embodiment of my invention are first the purity and brilliance of the colors obtainable; secondly blending the several colors in a single film without varying relief or thickness between the colors as in the "dyed gelatine relief" and "carbon" processes; thirdly securing accurate and automatic register of the several coloured photographic elements and fourthly 120 125 130

the quickness and simplicity of obtaining the composite print.

I have described somewhat in detail an illustrative method, embodying my invention, of producing the photographic elements and mechanical arrangements for supporting them and transferring the color from them, that may be employed, but it is understood that my invention is not confined 10 to these and that various changes may be made therein without departing from the spirit of this invention or the scope of my claims.

I claim:—

- 15 1. The method of making a coloured photographic print which consists in dyeing a film containing a volatile solvent by bringing it into contact with a photographic element holding a water-insoluble colouring matter soluble in said volatile solvent.
- 20 2. The improvement in the art of color photography which consists in producing a colored positive in relief in which coloring matter soluble in collodion is held in suspension in a finely divided condition, and then making a print therefrom on a sheet having a collodion film by pressing the film before it is thoroughly dry into contact with the colored surface of the positive.
- 25 3. The improvement in the art of color photography which consists in providing a sensitive film containing a pigment which is insoluble in the developer for said film, printing said film from the negative of the picture to be reproduced, developing said film, and then making a print therefrom by pressing the same into contact with another film containing means to absorb the pigment from the first film.
- 30 4. The improvement in the art of color photography which consists in first coloring a sensitive film, then printing and developing it in a developer which will not dis-
- 35 solve the pigment therein, and finally making a print therefrom by pressing the same into contact with another film containing a solvent for the pigment of the first film.
- 40 5. The improvement in the art of color photography which consists in providing a sensitive film containing a pigment which is insoluble in water but soluble in collodion, printing said film from the negative of the picture to be reproduced, developing said film in water, and then printing from said film upon a collodion coated sheet by contact before the collodion is thoroughly dry.
- 45 6. The improvement in the art of color photography which consists in providing a sensitive film having segregated fields each containing a differently colored pigment insoluble in water but soluble in collodion,
- 50 65 producing upon each field of said film a

correspondingly colored positive by printing said film from selective-color negatives and developing, and then making a print from said positives by successively superimposing them upon and pressing them into contact with a collodion film before the latter is thoroughly dry.

7. The improvement in the art of color photography which consists in providing a sensitive film having segregated fields each 75 containing a differently colored pigment in finely divided suspension and insoluble in the developer for said film, producing upon each field of said film a correspondingly colored positive by printing said film 80 from selective color negatives and developing the same, and then making a print from said positives by successively superimposing them upon and pressing them into contact with another film containing means 85 to absorb the pigment therefrom.

8. The improvement in the art of color photography, which consists in combining a dyestuff with a substance adapted to protect it from the action of the developer, incorporating the same in a sensitive film, printing and developing said film, and subsequently releasing said dyestuff from the said substance by the action of a suitable solvent; whereby the dyestuff is unaltered by the action of the developer for the sensitive film 90 but is set free at the proper time to produce the tinting effect required.

9. The improvement in the art of color photography, which consists in combining a 100 dyestuff with a resinous substance, incorporating the same in a sensitive film, printing and developing said film, placing another film containing a solvent for said resinous substance in contact with the first film, to cause the dyestuff to be transferred from the first film to the other film by the action of said solvent, and separating said films after such transfer.

10. The improvement in the art of color 110 photography, which consists in combining a dyestuff with a resinous substance, incorporating the same in a sensitive film, printing and developing said film, and placing a collodion film in contact with the first film before the collodion film is thoroughly dry.

11. The improvement in the art of making colored photographs by any process in which single-color positives are produced from selective-color negatives and then synthesized 120 into a polychrome composite, which improvement consists in introducing into the positive elements before they are printed a pigment containing a dyestuff and a substance to protect the dyestuff from the action 125 of the developer.

12. The improvement in the art of making colored photographs by any process in which single-color gelatine positives are produced from selective-color negatives and then syn- 130

thesized into a polychrome composite, which improvement consists in introducing into the gelatine of the positives before they are printed a pigment containing a dyestuff and 5 a substance to protect the dyestuff from the action of the developer.

13. The improvement in the art of making colored photographs by any process in which single-color gelatine positives are produced 10 from selective-color negatives and then synthesized into a polychrome composite, which improvement consists in introducing into the gelatine of the positives before they are printed a pigment containing a dyestuff and 15 a resinous substance.

14. The process of making colored photographs which consists in producing selective-color negatives of the thing photographed; producing therefrom single-color 20 positives on films which have been colored, before printing, with a pigment containing a dyestuff protected against action from the developer; and producing a polychrome composite from said positives.

25 15. The process of making colored photographs which consists in producing selec-

tive-color negatives of the thing photographed; producing therefrom single-color positives on gelatine films which have been colored, before printing, with a pigment 30 containing a dyestuff and a resinous substance; and producing a polychrome composite from said positives.

16. The improvement in the art of making a colored photograph which consists in producing selective-color negatives of the thing photographed, making therefrom positive images in color on a transparent sheet while the latter is held tightly stretched in a frame, and then superimposing the colored 40 images upon a base while the frame is held in successive positions relatively to the base to bring each image in succession directly over the base for registration with the other images. 45

In testimony whereof, I have hereunto affixed my signature, this twenty-fourth day of June, 1914.
